UNITED STATES PATENT OFFICE.

REINHARD T. FINGADO, OF MEXICO, MEXICO.

DEVICE FOR CENTERING TROLLEY-WIRES.

1,140,587.

Specification of Letters Patent. Patented May 25, 1915.

Application filed March 30, 1914. Serial No. 828,329.

To all whom it may concern:

Be it known that I, REINHARD T. FINGADO, a subject of the Emperor of Germany, residing at the city of Mexico, Mexico, have invented certain new and useful Improvements in Devices for Centering Trolley-Wires, of which the following is a specification.

This invention relates to a device for centering or lining up the trolley-wire or other parts of an overhead electric or other installation.

The primary object of the invention is to provide means for accurately centering a trolley-wire between the rails of a track, and to quickly detect any variation in the normal position of the trolley-wire or other overhead element.

The invention embodies the utilization of a mirror in connection with a graduated scale properly located with relation to the mirror, in the adjustment of the trolley-wire.

A further object of the invention is to provide a suitable frame adapted for adjustment upon the rails of a track, said frame serving as a convenient support for the mirror or mirrors employed.

The construction of the improved device will be fully described hereinafter in connection with the accompanying drawing which forms a part of this specification, and the features of novelty will be set forth and defined in the appended claims.

In the drawings: Figure 1 is a view in perspective of the improved device in position upon the rails of a track, and shown in connection with a portion of a trolley-wire. Fig. 2 is a diagram illustrating the manner of using the centering device, from the track level. Fig. 3 is a diagram illustrating the manner of using the device, the observation being taken from a point above the trolley-wire. Fig. 4 is a view in perspective of a modified form of mirror-supporting frame, and mirror. Fig. 5 is a diagram illustrating the manner of using the modified form of the device shown in Fig. 4, and, Fig. 6 is a plan view partly broken away of a further modification.

The reference numerals 1 and 2 designate the rails of a track. The mirror-supporting frame comprises parallel bars 3 and 4 connected at one end by a cross-bar 5 from which projects centrally an arm 6 having a downward extension 7 and recessed at its under edge as shown at 8 to fit upon the rail 2. The outer ends of the bars 3 and 4

are also recessed as indicated at 9 to adapt them to fit upon the opposite rail 1 as clearly shown in Fig. 1.

Numerals 10 and 11 designate two mirrors preferably of rectangular form, supported in any suitable way between the parallel sides of the frame and disposed to confront each other at an angle of approximately 45°.

Each mirror is provided with a central line 12 on either side of which the mirror is provided with graduations 13 arranged parallel with the central line 12 which latter corresponds to the normal or central position of the trolley-wire.

As will be obvious, the mirror-supporting frame may be readily adjusted upon the tread surface of the rails and occupies a position substantially parallel to the trolley-wire 14.

The utility and manner of using the device constructed as thus described may be explained as follows: As illustrated in the diagrams of Figs. 2 and 3, the trolley-wire is reflected upon the mirror 11, and if the wire is properly centered between the rails, this reflection will register with the central line of the mirror 11, and from this mirror will be reflected to the central line of the confronting mirror 10. As shown in Fig. 2, the central line is marked O, and the graduated lines 3 at the left of the central line are designated respectively L' and L'', while the corresponding graduations at the right of the central lines are designated R' and R'', respectively.

As shown by the diagrams, Figs. 2 and 3, the mirrors may be observed to determine the position of the trolley-wire either from the ground or track level as illustrated in Fig. 2, or from a point above the trolley-wire as illustrated in Fig. 3, the point of observation being designated in the drawing by the representation of eyes.

In the modification shown in Figs. 4 and 5, the supporting frame comprises parallel side bars 14 and 15 provided with confronting cleats or shelves 16 upon which the ends of a mirror 17 are supported adjustably. This mirror 17 is provided with a central longitudinal indicating line 18, and the inner side of one of the frame members shown in Fig. 4 is provided with a graduated scale, the central line of which is marked 0, and the lines on either side of the central line being designated 1, 2, 3, etc.,

indicating inches or other units of measurement. The parallel side members of the frame 14 and 15 are suitably braced by connecting rods 19 or like means.

5 As illustrated in Fig. 6, in lieu of the graduations upon the inner surface of one of the side members of the supporting frame, the mirror 17^a may bear a series of graduations, the central line of which is designated 10, and the lines on either side of the central line being designated 1, 2, 3, etc.

As will be apparent from the illustration and the foregoing description, if the trolley line is in its proper normal position, it will 15 be reflected upon the central line of the mirror, but if the wire is located to one or the other side of its proper alinement, such variation will be designated upon the mirror 17, in case a horizontal supporting mirror is 20 employed, or upon the angular mirror 11, as shown in Fig. 2, which reflects horizontally upon the confronting mirror 10.

By the employment of my improved device, any variation of the trolley wire from 25 proper adjustment may be readily detected, and overhead installations constructed and kept in proper adjustment with relation to the rails of the track.

In addition to the modified forms of the 30 invention illustrated in the accompanying drawing, the invention includes such further modifications and variations of the device as may be resorted to without departing from the terms of the claims, the invention 35 broadly including the employment of a mirror in connection with a graduated scale for testing the alinement of a trolley wire or

other overhead element of electric installation, whether said mirror be located in a horizontal plane as shown in Fig. 4 and 40 comprising a single mirror, or in an angular position as illustrated in Fig. 2, in which case two mirrors will be required as shown.

Having thus described my invention and in what manner the same is designed for 45 use, what I claim as new is:

1. A centering device for trolley wires comprising a supporting frame, reflecting means carried by the frame and provided with a fiducial line, and a scale co-acting 50 with the line.

2. A centering device for trolley wires comprising a supporting frame, confronting mirrors carried by the frame and arranged at angles to each other, each of the mirrors bearing a central longitudinal indicating line and a graduated scale co-acting with the line, and means for holding the frame against lateral movement on the rails of a 55 track.

3. A centering device for trolley wires comprising the combination with a supporting frame, of confronting mirrors arranged at angles to each other, each of said mirrors bearing a central longitudinal indicating line, and a graduated scale co-acting with 60 said indicating line.

In testimony whereof I have affixed my signature in presence of two witnesses.

REINHARD T. FINGADO.
